UNITED STATES PATENT OFFICE.

RUDOLF MALLINA, OF SAO PAULO, BRAZIL.

BOOKMARK.

Application filed October 9, 1922. Serial No. 593,438.

To all whom it may concern:

Be it known that I, RUDOLF MALLINA, a citizen of the Republic of Austria, and a resident of Sao Paulo, Brazil, have invented 5 new and useful Bookmarks, of which the following is a specification.

The present invention relates to improvements in bookmarks and has particular reference to means not only for providing a 10 mark in the book adapted to indicate where the reader stopped reading, but which also holds the leaves of the book in position while the book is being read, while in no way interfering with the turning over of the leaves 15 of the book. My device may be either permanently secured to a book or constructed in such a way that it can be slipped on and removed without difficulty.

The preferred forms of my book-mark are 20 illustrated in the accompanying drawing, in which Figure 1 shows one form of my book-mark detached from the book; Figure 2 the same form in its operative position in connection with a book; Figure 3 a modified 25 form of my book-mark; Figure 4 the latter form secured to a book, and Figure 5 a further modified form. While I have shown only a few forms in which the principle of 30 my invention may be expressed, I wish to have it understood that various changes or modifications may be made within the scope of the claims hereto attached without departing from the spirit of the invention.

The form illustrated in Figure 1 shows a 35 base (1) and a holding member (2). The base (1) is made of a single piece of wire bent into triangular shape so as to present two sides (3) and (4) of even length and a top member (6), a central portion (7) of 40 which is bent inwardly in U-shaped form. The apex (8) of the triangle is secured to a button (9) from which extends the holding member (2). The base described thus far is secured to the cover of the book as shown in 45 Figure 2; the cover being clamped between the U-shaped member (7) on the outside of the cover and the triangle on its inside so that the button (9) is disposed at a given distance from the edge of the cover. I preferably use the top edge of the rear cover for 50 holding the device.

The holding member (2) comprises a piece 55 of elastic wire, one end of which is secured to the button (9) while the other end extends slightly beyond the edge of the leaves of the book and terminates in an arm (11) running

substantially parallel to the edge of the book, and is provided with a finger (12) pointing inwardly adapted to be placed on top of a block of leaves. The use of this device is well 60 illustrated in Figure 2 from which it will be seen that the body part of the holding member (2) remains in contact with the cover and underneath the block of leaves, while the finger (12) rests on top of the leaves. 65 In doing so the whole wire is slightly twisted out of its shape and thus has a torsional tendency to return to its original position, whereby the leaves are held under tension. This tension is sufficient to prevent a turning 70 over of the leaves by such agencies as might interfere with the reading of a book in comfort, as for instance, the natural tendency of the leaves of a new book to close, or light air currents striking the leaves, as might 75 happen when the book is being read out of doors or while riding in a car. At the same time the tension is not sufficiently strong to prevent a turning over of the leaves by the reader since the latter in turning a leaf will 80 naturally pull down on the same before turning it so that it slips from under the finger (12) readily.

The modification shown in Figures 3 and 4 differs from the one thus far described only 85 in the construction of the base (13), which in this case is made of a solid plate, preferably of strong metal, the upper edge of which is turned on itself as shown at (14), whereby the clamping action is obtained. A 90 recess (16) in the plate allows of easy access to the best over portion (17) which facilitates the securing of the base to the book cover.

The modification shown in Figure 5 is 95 designed for the purpose of presenting a bookmark that may be permanently secured to the cover of the book. Its base consists preferably of a plate (18) of strong paper or cardboard which may be pasted to the cover 100 of the book, and in order to secure a firm hold for the holding member (2) the latter is provided with an extension (19) bent as at (21) so as to follow the outlines of the plate (18) and embedded therein. It will 105 be readily seen from the foregoing description that this book-mark may be constructed very economically and relies for its action principally on the torsional-tension created in a piece of elastic wire by twisting the 110 same. It utilizes the properties of such a wire to the best advantage and exercises a

pressure on the leaves to be held just sufficient for the purposes outlined hereinabove.

I claim:

1. A book mark comprising a base secured to a book cover and a resilient member rigidly secured thereto slanting relatively to one edge of the book cover and extending beyond the book leaves having an arm at its end turned at an angle of substantially less than ninety degrees and running substantially parallel to the edge of the book with a finger thereon for holding a block of leaves under torsional tension.
2. A book mark comprising a base secured to the inside of a book cover and a resilient member rigidly secured thereto slanting relatively to the side edge of the book cover and extending upwardly beyond the upper edges of the book leaves, an arm formed integral with said member and arranged at an angle of substantially less than ninety degrees relatively to said member and running substantially parallel to the upper edge of the book cover, and a finger carried by said member and arranged at an angle to the latter, said member arm and finger functioning to hold a block of leaves under torsional tension.
3. A book mark including a single piece of wire having its lower end connected to a

book cover, said wire extending upwardly from its lower end to the upper edge of the book cover and arranged at an inclination relatively to the side edge of the book cover, the upper portion of said wire being bent at an angle of substantially less than ninety degrees to form an arm running substantially parallel to the upper edge of the book, and a finger formed of said wire and arranged at an angle to the arm for holding a block of leaves under torsional tension.

4. A book mark including a base provided with a clip having a central portion designed to engage one side of a book cover and with side portions adapted to engage the opposite side of the book cover, relatively long connecting portions arranged between the central portion and the side portions to permit the central and side portions to be placed under torsional strain, and a substantially 7-shaped leaf engaging member connected to said base.

5. A book mark including a base provided with a substantially triangular shaped clip, the base of the triangle being provided with a depending portion arranged between the sides of the triangle and extending toward the apex of the triangle, and a leaf engaging member connected to said base.

RUDOLF MALLINA.
